UNITED STATES PATENT OFFICE.

JOSEPH J. NELSON, OF KENT, OHIO.

SAFETY PLUG RETAINER.

Application filed December 29, 1922. Serial No. 609,665.

To all whom it may concern:

Be it known that I, JOSEPH J. NELSON, a citizen of the United States, residing at Kent, in the county of Portage and State of Ohio, have invented certain new and useful Improvements in Safety Plug Retainers; and I do hereby declare the following to be a full, clear, and exact description of the invention, such as will enable others skilled in the art to which it appertains to make and use the same.

The present invention relates generally to plugs for boilers and other structures, and aims to provide novel and improved means for preventing a plug from being blown out of its hole or dislodged due to the screw-threads giving way, or while the plug is being unscrewed.

The improvements are especially useful in connection with the wash-out or clean-out plug of a boiler, although the device can be used for other purposes for which it is suitable, and an object of the invention is the provision of a simple, inexpensive and efficient device for retaining the plug in place against accidental displacement from its position in or at the hole provided for it. The device will retain the plug in place even though the screw-threads give way, and, furthermore, when the plug is being unscrewed, the device will prevent the plug from dropping when it leaves the hole.

It is also an object of the invention to provide such a device which can be incorporated in plug structures without prohibitive trouble or expense, so that the improvements can be embodied in boilers already in use at moderate cost and little work for the installation.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a median section of the plug and other parts, taken on the line 1—1 of Fig. 2, portions being shown in elevation.

Fig. 2 is an inner or rear view.

Fig. 3 is an elevation of the plug and retainer member showing them in position for the insertion or removal of such member.

In the drawing there is illustrated a wash-out or clean-out plug 7 of a boiler, which screws into the hole 8 in the shell 9 of the boiler, although the illustration can be taken as typical of any plug for which the device is appropriate.

The retainer member 10 comprises a bolt or rod having the screw-threaded terminal or stem 11 to project centrally through the hole, and the plug 7 is formed with a screw-threaded bore or hole 12 extending from its inner or rear end to receive the stem 11. The screw-threads of the stem 11 and bore 12 of the same pitch as the screw-threads of the hole 8 and periphery of the plug, whereby the plug will screw on the stem 11 while being screwed into the hole 8, the axial rate of travel of the plug for both sets of screw-threads being the same.

The retainer member 10 has its other terminal portion 13 bent back into the form of a hook, whereby the terminal portion 13 can abut the inner surface of the wall or shell 9 at one side of the hole 8, preferably below said hole. The portion or finger 13 abutting the shell or wall 9 will prevent the member 10 from moving outwardly in the hole 8, and even though the screw threads between the plugs and shell 9 should give way by corrosion or weakening, the plug being threaded on the member 10 will be held in the hole, so as not to be blown out or dislodged.

In order to prevent the member 10 from turning when the plug is screwed into or out of the hole 8, a bifurcated or notched member 14 is disposed at the inner surface of the shell or wall 9 at one side of the opening or hole 8, so that the notch thereof can receive the end of the finger or portion 13, as seen in Figs. 1 and 2, to prevent the member 10 from turning. The member 14 has a stud 15 projecting into an aperture 16 formed in the wall or shell 9 at one side of the hole 8, and said stud 15 is secured in the aperture 16 by the welded joint 17, or the like.

The retainer member will not only prevent the plug from being blown out or dislodged while in the hole 8, but will also prevent the plug from dropping when the plug is unscrewed. Thus, the stem 11 projects outwardly through the hole 8 beyond the outer surface of the shell or wall 9, so that when the plug is completely unscrewed from the shell or plate 9, it is still screwed on the retainer member, which prevents the plug from dropping. Now, by shifting the

2
plug transversely of its axis, as seen in Fig. 3, the retainer member can be withdrawn through the hole 8, the width of such member being slightly less than the diameter of 5 the hole. This enables the plug and retainer member to be removed as a unit, and they are readily applied by inserting the retainer member through the hole with the plug screwed partially on the stem 11. The plug 10 and retainer member are then shifted to bring the plug concentric with the hole 8, and to bring the finger or portion 13 in the notch of the keeper member 14. Then, when the plug is turned it can be screwed on 15 the stem 11 and into the hole 8.

All that is necessary to incorporate the improvements is to provide the threaded bore 12 in the plug and to fasten the member 14 to the shell or seat 9.

20 Having thus described the invention, what is claimed as new is:—

1. A plug to screw in the hole of a wall, and retaining means carried by the plug to abut the inner surface of said wall and 25 arranged to be removed through said hole with the plug.

2. A plug to screw in the hole of a wall, and a retainer member to engage said wall having a screw-threaded connection with 30 the plug and arranged to be removed through said hole with the plug.

3. A plug to screw in the hole in a wall, and a retainer member threaded in the plug and having a portion to abut the inner 35 surface of said wall, said member and portion thereof being arranged to be removed through said hole with the plug.

4. A plug having screw threads thereon to screw into a hole in a wall, and a retainer member having a screw-connection 40 with the plug and a portion to engage said wall, the screw threads between said member and plug being of the same pitch as the first named screw threads of the plug, said 45 member and portion thereof being arranged to be removed through said hole with the plug.

5. A plug to screw into a hole in a wall, and a retainer member having a terminal 50 screw-threaded in the plug and a bent back terminal to abut the inner surface of said wall, said member being arranged to be removed through said hole with the plug.

6. A plug to be screw-threaded in a hole

in a wall, a retainer member having a 55 screw-threaded connection with the plug and a portion rigid therewith to bear against the inner surface of said wall, said member and portion thereof being arranged to be removed through said hole with the plug, 60 and a member to be disposed at the inner surface of said wall at one side of said hole to engage said portion of the retainer member to prevent the retainer member from 65 turning.

7. A plug to screw into a hole in a wall, a retainer member having a terminal portion screw-threaded in the plug and having a rigid bent back terminal portion to abut the inner surface of said wall, said member being arranged to be removed through said hole with the plug, and a notched member to be carried by said wall at the inner surface thereof at one side of said hole for receiving the last named terminal portion 75 of said retainer member.

8. A retainer member for a plug having a threaded portion to engage the plug and a portion to abut the inner surface of a wall in which the plug is screwed, said member 80 being arranged to pass through the plug hole when carried by the plug.

9. A retainer member for a plug having a screw-threaded terminal on which the plug can be screwed, and having a bent back terminal to abut the inner surface of a wall in which the plug is screwed, said member being arranged to pass through the plug 85 hole when carried by the plug.

10. A retainer member for a plug having a screw-threaded terminal on which the plug can be screwed, and having a bent back terminal to abut the inner surface of a wall in which the plug is screwed, the first-named terminal of the retainer member being sufficiently long to project outwardly through a hole for the plug in said wall beyond the outer surface of the wall, said member being arranged to pass through the plug hole 90 when carried by the plug.

In testimony whereof I have signed my name to this specification in the presence of two subscribing witnesses.

JOSEPH J. NELSON.
